STANDPIPE SYSTEM

William F. Conran, Brooklyn, N. Y.

Original application July 10, 1928, Serial No. 291,628. Divided and this application April 28, 1931. Serial No. 533,398

5 Claims. (Cl. 169—5)

The present invention relates to fire-extinguishing standpipe systems for buildings such as disclosed, for example, in U. S. Patents Nos. 816,152 and 1,253,005, granted to me March 27, 1906 and January 8, 1918, respectively.

In a system of this character a standpipe extends vertically in the interior of the building, passing upward through the various floors, and is provided at the several stories or levels with 10 branches having nozzles, these branches having valves and a remote control system being provided for opening said valves selectively from a control station in the basement or lower portion of the building. By hydraulic means, the standpipe, 15 together with all its nozzles, can be raised or lowered in order to change the striking distance of the stream delivered from any one of the nozzles, to enable the stream to clear obstructions, to enable the stream to be played close to the 20 floor or at any height that may be found desirable when subduing a fire at a distant point of the floor, and in general to provide a vertical range through which the stream can be moved to attack a fire in the most effective manner. In 25 addition, the standpipe with its nozzles can be turned about its vertical axis to enable a stream or streams to be delivered in any lateral direction or to cause the streams to sweep back and forth laterally to cover the entire area to be 30 protected.

The purpose of this invention is to provide, in combination with a standpipe system having either or both of these features, a means for enabling the various nozzles of the system to be 35 set and locked at any selected inclination in respect to the horizontal. This feature greatly increases the value of such fire-protection systems, since at different floors there are apt to be different distances between the floor and ceiling lines, and also because at certain floors there 40 may be part-height partitions or obstructions which can be taken into account in the installation of the system, or in the re-setting of the 45 nozzles from time to time depending upon changes in the conditions under which a fire may have to be fought at one floor or another.

For any given water pressure that can be delivered at any floor the theoretical horizontal 50 reach of the stream that would be delivered from that nozzle can be ascertained for any degree of inclination of the nozzle, and it is safe to assume that the stream will actually carry at least 65% of this distance. In addition, however, there must 55 also be considered the height of the ceiling which must be cleared by the highest point of the curve described by the stream, if the stream is to attain its maximum reach. Consequently, the 60 ability to set the various nozzles at any and different inclinations and to secure them rigidly in their

various positions, so that they will not be disturbed, is an important advance in the art.

The features of construction employed in the carrying out of the invention can best be described in the body of the specification.

In the accompanying drawings, forming part hereof:

Fig. 1 is a fragmentary elevation of a standpipe system to which the invention is applied, certain parts being broken away and others in section, 70 and portions of the building being represented in section;

Fig. 2 is a section taken on the line 2—2 of Fig. 1;

Fig. 3 is an enlarged view, principally in vertical section, of one of the nozzle branches or outlets of the system, the nozzle being shown in full lines in a horizontal position and in broken lines at an upward inclination, to indicate a range of angular settings;

Fig. 4 is a plan view of the nozzle branch, partly in section; and

Fig. 5 is an end view of the nozzle branch, with portions broken away.

Referring now to Fig. 1, the standpipe comprises a plurality of pipe sections 1 joined by nozzle-carrying fittings 2 and the control fitting 3, the lowermost pipe section carrying at its lower end the piston 4 slidably mounted in the supporting and lifting cylinder 5. The standpipe is 85 slidably and rotatably movable in openings in the floors 7, where suitable bearing sleeves (not shown) may be provided for its guidance.

Each of the nozzle-carrying fittings 2 comprises a discharge branch 8, at the end of which is 95 mounted one of the nozzles 9 to be described in detail hereinafter, and in which is mounted a valve 10 for controlling flow through the nozzle. Each of the valves 10 is controlled by a piston 11, which is normally held in its lower position by a spring 12 and raised by the admission of pressure fluid from one of the control pipes 13 to the cylinder below the piston. Each control pipe 13 passes through the interior of the standpipe to the control fitting 3, through the wall 100 of which it passes to the exterior of the standpipe, and at this point is provided with a three-way operating valve 14. The several control pipes 13 may be connected to a manifold 17.

A control pipe 15 passing through the control fitting and having an exteriorly mounted three-way operating valve 16 serves to supply pressure fluid to the cylinder 5 below the piston 4 for the purpose of raising the standpipe. This control pipe is shown connected with the manifold at 19.

The inlet ends of the several control pipes 13 may be connected to an annular manifold 17.

Rotation of the standpipe can be effected by using the pipe 19 as a lever, although a separate 120

lever for this specific purpose may be attached to the standpipe.

A connection 25 provided with a valve 26 serves to admit water to the standpipe and to the manifold 18, the latter being shown connected with the connection 25 by a branch 28, containing a valve 29. Manifestly, these particular arrangements are not essential, since, for example, the control pipes 13 and 15 can be arranged to receive operating liquid from the interior of the standpipe as illustrated in my prior patents. A hose 31 is shown for supplying water under pressure from the city mains or other source to the connection 25.

15 Figs. 3 to 5 illustrate in detail one of the nozzle branches which are carried by the standpipe at the several stories or levels of the building. The construction being the same in the various discharge branches of the standpipe system, a description of one of the nozzle branches will suffice for all.

The discharge branch 8 is externally threaded at 42, and the end of the branch forming the wall of the discharge orifice is machined to form a 25 convex bearing surface 43 the contour of which is a portion of the surface of a horizontal cylinder.

The nozzle 9 is formed with a belled base 44, one face of which is machined to a concave bearing surface 45 of the same character and radius as the surface 43, against which it is adapted to seat. The opposite face of base 44 is machined to a convex spherical surface 46. A coupling and clamping collar 47 is provided with a hexagonal 35 base 48 and/or with projections 60, to receive a heavy wrench. This collar is screwed tightly onto the threaded end of the branch 8 so as to clamp the nozzle 9 immovably at any selected deflection.

40 The collar is formed with an aperture 49 larger in diameter than the tubular portion of nozzle 9. The under surface 50 surrounding the aperture 49 is machined to a concave spherical curvature 50 adapted to engage the spherical surface 46 of the nozzle base 44. An index 51 is stamped on 45 the face 46 of the nozzle base, said index cooperating with the inner edge of the aperture 50 to show in degrees the angle of inclination of the nozzle.

50 From the foregoing description it follows that the nozzle 9 can be adjusted to any desired vertical angle and clamped in the desired position by tightening the screw collar 47. The cylindrical surfaces 43 and 45 prevent lateral displacement, while the spherical surfaces 46 and 50 form a fluid-tight joint regardless of the position of rotation of the collar 47. In order to keep the diameter of collar 47 to a minimum, the base 44 of the nozzle is preferably made eccentric with respect to the longitudinal axis of the nozzle, as indicated in Figs. 3 and 5. As shown in Fig. 3, the nozzle is adjustable at any vertical inclination between a horizontal and a maximum upwardly inclined position.

60 The invention presented in this application is a division of my application filed July 10, 1928, Serial Number 291,628.

I claim:

1. In a fire-protection standpipe system constituting an installation in a building, the combination with a movable standpipe extending vertically in the building, and supported for oscillation about its axis, of valved discharge branches

carried by said standpipe at the various levels, said branches having cylindrically curved end surfaces with their axes of curvature substantially horizontal, nozzles applied to said branches and located in substantially the same vertical plane, each of said nozzles having a base formed with a complementary cylindrically curved surface to seat against one of said end surfaces so that the nozzles can be shifted in a vertical plane to different deflections, and coupling members which lock the nozzles to the branches at the deflections at which they are set.

2. In a fire-protection standpipe system, the combination of a discharge branch of the system, said discharge branch having a cylindrically curved end surface, a nozzle having a base formed with a complementary cylindrical surface adapted to seat against the first-named surface and with an external spherically curved surface, and a screw coupling member adapted to clamp 95 the nozzle rigidly to the branch, said coupling member having an internal surface formed to cooperate with the spherically curved surface of the nozzle base.

3. In a fire-protection standpipe system, the combination of a discharge branch of the system, said discharge branch having a cylindrically curved end surface, a nozzle having a base formed with a complementary cylindrical surface adapted to seat against the first-named surface 105 and with an external spherically curved surface, a deflection indicating scale on said base, and a screw coupling member adapted to clamp the nozzle rigidly to the branch, said coupling member having an internal surface formed to cooperate 110 with the spherically curved surface of the nozzle base.

4. A fire-protection standpipe system including in combination a standpipe extending vertically in the building, valved discharge branches at the 115 several levels of the building, means for oscillating the standpipe about its axis and for moving the standpipe vertically to shift the positions of the branches with respect to the levels of the building, a nozzle for each discharge branch, all 120 of the nozzles being located in substantially the same vertical plane, connections between the nozzles and their respective branches, including means for changing the vertical deflection and preventing horizontal displacement of each nozzle 125 with respect to the standpipe, and releasable locking means for holding each nozzle in adjusted position.

5. A fire-protection standpipe system comprising 130 a standpipe extending vertically in a building, valved discharge branches at the several levels of the building, remote control means for the valves of said branches, a nozzle for each discharge branch, said nozzles being located in substantially the same vertical plane, connections 135 between the nozzles and their respective branches, each of said connections being adjustable to change the vertical deflection of its associated nozzle and hold said nozzle against horizontal movement, releasable locking means for holding each nozzle in adjusted position, and means for moving the standpipe about its axis to change the positions of all discharge branches and nozzles simultaneously.
